ABRADING MACHINE WORK SUPPORT

Loren E. Thompson, Parkersburg, W. Va.

Original application March 12, 1943, Serial No. 478,925. Divided and this application September 16, 1943, Serial No. 502,667

4 Claims. (Cl. 51—233)

This invention relates to abrading machines and more particularly to a work support or carriage, and is a division of my copending application Serial Number 478,925 filed March 12, 1943 for Abrading apparatus.

An object of this invention is to provide a reciprocal work support or carriage which is so constructed and arranged that a maximum movement may be obtained within a minimum amount of space.

Another object of this invention is to provide in a reciprocal work support or carriage, an improved hydraulic operator for reciprocating the carriage which will eliminate any wearing of parts such as are involved in screw operators.

A further object of this invention is to provide a hydraulic operator for a reciprocal work support which involves a stationary cylinder, a rotary slotted cylinder or sleeve, and a floating piston which is slidable in the rotary cylinder and connected to a central portion of the work support or carriage.

The invention consists of the novel construction, combination and arrangement of parts as will be more specifically referred to and illustrated in the accompanying drawings wherein is shown an embodiment of the invention, but it is to be understood that variations, modifications and changes may be resorted to which fall within the scope of the invention as claimed.

In the drawings:

Figure 1 is a fragmentary front elevation of an abrading machine embodying a work support constructed according to an embodiment of this invention.

Figure 2 is a fragmentary side elevation of the machine.

Figure 3 is a longitudinal section partly in detail showing the operator for the work support.

Figure 4 is a sectional view taken on the line 4—4 of Figure 3.

Figure 5 is a bottom plan of the work support.

Figure 6 is a top plan partly broken away of the work support.

Figure 7 is a top plan of the cradle or base for the work support.

Figure 8 is a fragmentary front elevational of the cradle or base for the work support, and

Figure 9 is an enlarged longitudinal section of the operator for the work support.

Referring to the drawings, the numeral 10 designates generally a frame structure having mounted thereon a rotatable abrading wheel 11 which is provided with an abrasive member 12. The frame structure 10 has secured thereto a

saddle 13, the details of which are more specifically set forth in my copending application supra. The saddle 13 is adapted to have movement at right angles to the face of the abrader 12 so as to move the work support to be hereinafter described toward or away from the abrading member.

The saddle 13 has mounted thereon a cradle or work supporting base 14. In the present instance, 10 the saddle 13 is formed with an arcuate or concave seat 15 and the base or cradle 14 is formed with a convex outer side 16 which is adapted to engage in the seat 15. The cradle 14 is adapted to be tilted or rocked in the seat 15 and locked in 15 the adjusted position to dispose the work support on the desired angle with respect to the working face of the abrader 12.

The cradle or base 14 is formed with a flat upper side 17 and is also formed with a keyway 20 or guide 18 of substantially truncated V-shaped configuration. A work support generally designated as 19 is adapted to slidably engage on the base or cradle 14. The work support 19 includes a substantially rectangular body 20 of elongated 25 configuration which is formed with a key-shaped slide 21 engaging in the keyway 18. A shim 22 is adapted to be interposed between one side of the slide or key 21 and the adjacent side of the keyway 18.

30 In order to provide a means whereby the work support 19 may be reciprocated back and forth in a direction parallel with the working face of the abrader 12, I have provided a hydraulic operator, generally designated as 23. The operator 23 includes a cylindrical bore 24 which is formed lengthwise of the cradle or base 14. A cylinder 25 is rotatably mounted in the bore 24 and is adapted to abut at the opposite ends thereof against anti-friction thrust members 26 and 27. 35 End plates or heads 28 and 29 are secured to the opposite ends of the cradle or base 14 and close the ends of the bore 24 and the cylinder 25.

The head or end plate 28 has connected thereto one end of a liquid delivery pipe 30 which is connected to a suitable source of liquid under pressure and the head or end plate 29 has connected thereto one end of a liquid delivery pipe 31 which is connected to a suitable source of liquid under pressure. The liquid from the pipes 30 and 31 is 40 adapted to be discharged through the annular thrust members 26 and 27 into the interior of the cylinder 25.

The cylinder 25 is formed with an elongated slot 32 which is of spiral configuration and a 45 work support operating piston 33 is slidable in

the cylinder 25. The piston 33 is of the floating type and is formed at the opposite ends thereof with abutments 34 and 35 to engage against the correlated heads or end plates and to hold the adjacent end of the piston 33 in slightly spaced relation with respect to the end plates. The piston or operator 33 has secured thereto an upwardly extending connecting member 36. The connecting member 36 is formed at its lower end with a T-shaped lower portion 37 engaging in an inverted T-shaped passage 38 formed in the piston 33. The stem 39 of the connector 36 extends upwardly through the slot 32 and is formed integral with a slide block 40 which is substantially longer than the connecting member 36, as shown in Figure 9.

The slide block 40 has formed integral therewith an upwardly projecting arm 41 which is adapted to engage in a recess 42 which is formed in the slide member 21. The base or cradle 24 is formed with an elongated lengthwise extending slot 43 within which the slide member 40 is adapted to slidably engage. The slide member or key 21, as shown in Figure 5, is preferably of hollow construction being formed with downwardly divergent side walls 44, end walls 45 and intermediate bracing walls 46. A central transverse wall 47 connects the side walls 44 together and the recess 42 is formed in the central wall 47. The wall or base 47 is also formed with a horizontal transversely disposed and forwardly opening passage 48 within which a pin 49 is adapted to engage.

The pin 49 is formed at its inner end with a reduced threaded stud 50 threadably engaging in a threaded socket 51 formed at the inner end of the passage 48. The pin 49 is formed at its outer end with a nut socket 52 and is adapted to extend through an opening 53 formed in the lug or extension 41. The body 20 of the work support 19 is formed in the upper flat side 54 thereof with a plurality of parallel lengthwise extending T-shaped slots 55 and is also formed in the forward face 56 thereof with at least a pair of lengthwise extending T-shaped slots 57. The rear side of the work support 19 is provided with a rearwardly extending part 58 having the rear side 59 thereof disposed on a downwardly and outwardly inclined angle so that sufficient clearance will be provided for the removed material to drop downwardly between the abrading face of the abrader 12 and the rear side of the work support 19. The upper flat side 54 of the work support is also formed with a pair of transversely extending rectangular recesses 60 disposed closely adjacent the opposite ends of the support 19, as shown in Figure 6.

The cradle or base 14 is adapted to have the forward and rear sides thereof sealed by means of a pair of flexible shields 61 and 62. The shield 61 is secured as at 63 to the upper portion of the base or cradle 14 and is then wound about a spring roller 64 secured by supporting brackets 65 to the saddle 13. The shield 62 which is of flexible construction is secured as at 66 to the upper portion of the base or cradle 14 and is wound about a spring roller 67 which is carried by brackets 68 secured to the saddle 13.

In the use and operation of this device, the work is adapted to be secured by headed fastening members to the upper side 54 of the support 19 in a position where the work may be engaged by the forward face of the abrader 12. The sup-

port 19 is reciprocated back and forth with respect to the base or cradle 14 by fluid pressure in the cylinder 25. As the piston 31 moves lengthwise of the cylinder 25, the cylinder 25 will be rotated under the movement of the connecting part 39 which is secured to the piston 33. The spiral slot 32 has such a pitch that the piston 33 will prevent any fluid in the slot 33 from entering the slot 43.

With a work support as hereinbefore described connected to a hydraulic operator which is entirely contained within the base or cradle 14, it is possible to obtain a maximum movement of the work support within a limited space due to the fact that no projecting operating elements extend beyond the ends of the base 14. In addition to this, by providing the hydraulic operator, there will not be the usual wear on the operator as is the case with threaded operators or geared operators.

It will be understood that suitable valves may be interposed in the pipe lines 30 and 31 to provide for the necessary reciprocation of the support 19 and such valves may be regulated in any suitable or well known manner.

What I claim is:

1. A reciprocal work support comprising in combination a saddle, a cradle rockably carried by said saddle, a work support, means slidably mounting said support on said cradle, and means disposed entirely within said cradle and connected to said support for reciprocating the latter.

2. In an abrading machine, an elongated horizontal base formed with a lengthwise slot in the upper side and a lengthwise cylindrical opening communicating with said slot, a reciprocal elongated work support slidably carried by said base, a rotatable cylinder in said opening and formed with an elongated spiral slot, thrust means at the opposite ends of said cylinder, a piston slideable in said cylinder, and a connecting member extending through both of said slots connecting said piston with said work support whereby reciprocation of said piston will reciprocate said work support, and means discharging fluid under pressure into said cylinder at opposite ends of said piston.

3. In an abrading machine, an elongated horizontal base formed with a lengthwise guide and a lengthwise slot within said guide, a work support including an elongated body and a slide engaging in said guide, said base having an elongated lengthwise opening communicating with said slot, a spirally slotted cylinder rotatable in said opening, a piston slideable in said cylinder, said piston having a T-shaped passage therein, a connecting member formed with a T-shaped lower portion fixedly mounted in said T-shaped passage and slidably engaging in said slot, a lug carried by said connecting member, said slide having a downwardly opening recess and said lug engaging in said recess, and a pin removably carried by said slide engaging said lug for securing said lug to said slide.

4. In an abrading machine, in combination an elongated saddle formed with a transversely concave seat in the upper side thereof, a cradle formed with a convex lower side seated in said seat, flexible spring-pressed shields connected to said saddle and said cradle, a work support slideable on said cradle, and means entirely within said cradle for reciprocating said work support.

LOREN E. THOMPSON.
